WATCH

Michael Laurence Bateman, Harrow, England,
assignor to Adie Brothers Limited, Birmingham,
England

Application January 20, 1933, Serial No. 652,677,
and in Great Britain May 25, 1932

3 Claims. (Cl. 58—88)

This invention comprises improvements connected with watches, and has for its object to provide an arrangement whereby the watch movement is sealed. It has been found that the repair of watch movements have often been undertaken by those who are unskilled in the art, with the result that the user is dissatisfied with the watch not knowing that it has been repaired in an unskilled manner. The present invention has been designed to overcome this defect in that the movement is issued sealed to the purchaser, who in order to obtain an efficient repair or replacement of the movement returns it sealed to the maker or his authorised agent, showing that the seal has been unbroken when the necessary repairs or replacement of the movement is effected. By this arrangement the maker will know whether the movement has been tampered with, whilst at the same time the user will be in a position to obtain a much more efficient service for the repair of the movement.

Referring to the drawing:—

Figure 1 is a section of a watch fitted with a movement ring according to this invention.

Figure 2 is a perspective view of the movement ring with the cover fitted, whilst,

Figure 3 is a perspective sectional view showing the arrangement for positioning the cover in its correct position.

In carrying the present invention into practice as shown upon the accompanying drawing, the movement 3 which is shown diagrammatically, is provided with the usual movement plate 4.

The movement is fitted into the movement ring 5, the upper edge of which is provided with a recess 6 to accommodate the movement plate 4. The upper edge of the movement ring 5 is provided with a shoulder 7 which is positioned within the watch case 8.

The rear edge of the movement ring 5 is recessed at 9, whilst the usual screws 10 which screw into the movement and are used for retaining the watch movement in its casing by the heads of the screws engaging the casing are arranged, instead to engage the recess 9 and thereby lock the movement 3 in the movement ring 5.

Disposed at the rear of the movement 3 and in the recess 9 is a cover 12 which may be of celluloid or other suitable material, after which the edge 13 of the movement ring 5 is spun or otherwise turned over to lock the cover 12 in position.

The cover 12 has provided therein an aperture 14 which is adapted to register with the movement regulator arm so that the watch can be adjusted with the cover 12 in position.

In order that the cover 12 may be correctly positioned in the movement ring 5, the movement ring 5 is provided with a small projection 15 as shown in Figure 3, whilst a small portion is cut out of the cover 12 which is adapted to register with the projection 15, thereby correctly positioning the aperture 14 in relation to the movement regulator arm.

It will be seen by the before described arrangement that a sealed movement is provided and that any unauthorised tampering or repair of the movement can readily be detected, it being impossible to remove the movement 3 out of the movement ring 5 without first of all removing the cover 12 which is sealed in position in the movement ring 5.

I claim:—

1. Improvements connected with watches, comprising in combination, a watch movement, a movement ring, a recess formed at the rear of said movement ring, means for engaging the watch movement and the recess formed at the rear of said movement ring for securing said movement ring to the movement and a cover secured in the recess formed in the rear of the movement ring to prevent the unauthorised detachment of the movement ring from the movement.

2. Improvements connected with watches, comprising in combination, a watch movement, a movement ring, a recess formed in the front of said movement ring to receive the movement plate, a recess formed in the rear of said movement ring, means for engaging the watch movement and the recess formed at the rear of said movement ring for securing said movement ring to the movement and a cover secured in the recess formed in the rear of the movement ring to prevent the unauthorised detachment of the movement ring from the movement.

3. Improvements connected with watches, comprising in combination, a watch case, a watch movement, a movement ring, a recess formed in the front of said movement ring to receive the movement plate, a recess formed in the rear of said movement ring, means for engaging the watch movement and the recess formed at the rear of the movement ring for securing said movement ring to the movement and a cover secured in the recess formed in the rear of the movement ring to prevent the unauthorised detachment of the movement ring from the movement.
